COMBINED PENLIGHT AND TONGUE DEPRESSOR HOLDER

Lazzaro A. Fattori, Woodcliff Lake, N.J., assignor to
William F. Blake, Inc., Summit, N.J., a corporation of
New Jersey

Filed Dec. 18, 1968, Ser. No. 15,047

Term of patent 14 years

Int. Cl. D24—03; D26—04

U.S. Cl. D83—12

FIG. 1

FIG. 5

FIG. 2

FIG. 3

FIG. 4

FIG. 6

FIG. 1 is a perspective view of a combined penlight and tongue depressor holder;

FIG. 2 is a plan view as seen from the top of FIG. 1;

FIG. 3 is a side elevation thereof;

FIG. 4 is a bottom plan view thereof;

FIG. 5 is a front end elevation thereof; and

FIG. 6 is a rear end elevation thereof.

The broken lines representing the penlight and tongue blade are shown for illustrative purposes.

I claim:

The ornamental design for a combined penlight and tongue depressor holder, as shown and described.
